UNITED STATES PATENT OFFICE

ISAIAH A. EAKINS, OF PLEASANTON, TEXAS, ASSIGNOR TO GENERAL AMERICAN TANK CAR CORPORATION, OF CHICAGO, ILLINOIS, A CORPORATION OF WEST VIRGINIA

REVERSIBLE DISPLAY DEVICE

Application filed June 9, 1930. Serial No. 459,965.

My invention relates to a device for use where it is desired to display, selectively, for observation, different display matter, as for example in the case of tank cars where it is desired that a placard, or the like, display the information as to whether or not the tank is loaded or empty.

My objects are to provide a device whereby matter may be displayed, selectively, by adjusting the member of the device, presenting such matter, into different positions; to provide a simple and economical construction of such device and by which manipulation, to selectively display the different display matter, may be effected quickly and readily and when manipulated to the desired position will be maintained in set position; and other objects as will be manifest from the following description.

Referring to the accompanying drawings: Figure 1 is a view in front elevation of a display device embodying my invention.

Figure 2 is an edge view thereof; and Figure 3, a broken section taken at the line 3—3 on Fig. 1 and viewed in the direction of the arrows.

According to the illustrated embodiment of my invention the device comprises a bracket 4 having oppositely extending legs 5 and 6 at its opposite ends, the leg 5 being provided for attachment to a supporting structure as for example a tank car at any suitable place thereon.

The device also comprises a plate 7 forming a placard upon the opposite sides of which the matter to be selectively displayed, as for example the word "loaded" and "empty" as in the case of its use on a tank car, is presented, as for example by pasting thereon labels bearing the display matter.

The plate 7 at one end thereof is provided with a stud 8 shown as forming the terminal portion of a split-clip 9 the legs of which embrace an edge of the plate 7, the clip being secured to the plate by bolts 10.

The stud 8 which is formed at its outer end with an enlargement 11, shown as in the form of a ball, extends through an elongated slot 12 formed in a ledge-member 13 carried by the bracket 4, the enlargement 11 being of such

size that it prevents withdrawal of the stud 8 from the slot 12, the plate 7 thus being pivotally associated with the bracket and adapted to be swung in a direction away from the body-portion of the bracket to permit of the reversing of the plate 7 by rotatably adjusting it.

The ledge-member 13 is shown as formed of a strip of metal through an end of which the slot 12 extends. The strip is secured at 60 its other end to the main portion of the bracket by the bolts 15, its slotted end portion, after the introduction of the stud 8 into it, being bent into the shape shown to render the slot 12 closed against sliding of the stud 65 8 therefrom.

Means are provided for holding the plate 7 in either of its positions of rotatable adjustment, these means, in the embodiment shown, comprising a spring-catch in the form of a flat spring strip 16 secured at one end flatwise against the leg 6 by bolts 17, its opposite end extending over the edge of the plate 7 and having a deflected catch-forming projection 18. The edge of the plate 7 adjacent the spring-catch contains a recess 19 into which the catch extends preventing tilting of the plate laterally, the catch-forming projection 18 lapping the front side of the plate 7 and holding it against swinging away 80 from the bracket 4. As will be understood, the catch is adapted to be flexed into a position for permitting the plate 7 to be swung forwardly for rotation at its stud 8 when it is desired to reverse the plate 7.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

1. In a device of the character described, the combination of a support having legs extending forwardly and rearwardly, respectively, from its opposite ends and having an apertured portion extending at an angle to the intermediate portion of said support, a member for presenting on its opposite sides 95 100

- matter to be displayed, a stud rotatable in the aperture in said apertured portion and having a head, said member being adapted to swing outwardly from said support, and a catch device on the rearwardly extending one of said legs for holding said member in either of its positions of rotatable adjustment.
2. In a device of the character described, the combination of a supporting member containing an opening, a second member for presenting on its opposite sides matter to be displayed and having a stud extending loosely in said opening, an abutment engaged by said stud and limiting lengthwise movement of said second member, and a spring catch positioned to be engaged by said second member for holding the latter in either of its positions of adjustment.
3. In a device of the character described, the combination of a supporting member containing an opening, a second member for presenting on its opposite sides matter to be displayed and having a head connected with the body of said second member by a neck, said second member loosely extending at its neck portion in said opening to adapt said second member to be rotated on said supporting member and to be bodily rocked on the latter, an abutment engaged by said head and limiting lengthwise movement of said second member, and a spring catch positioned to be engaged by said second member for holding the latter in either of its positions of adjustment.
4. In a device of the character described, the combination of a supporting member containing an opening, a second member for presenting on its opposite sides matter to be displayed and having a head at its lower end connected with the body of said second member by a neck, said second member loosely extending at its neck portion in said opening to adapt said second member to be rotated on said supporting member and be bodily rocked on the latter, an abutment below and engaged by said head, and a spring catch positioned to be engaged by said second member for holding the latter in either of its positions of adjustment.
5. In a device of the character described, the combination of a supporting member having an opening, a display member adapted to be disposed at an inclination in reversed positions and having a stud member adjacent the lower end thereof, means disaligned with the stud having supporting engagement with the display member in said reversed positions at a distance above the lower end of the display member and said stud member being loosely disposed in said opening to thereby adapt the display member to be rotated and to be bodily rocked on the supporting member in a direction away from the zone of support to effect the said reversal.
6. In a device of the character described,

the combination of an upstanding supporting member, means extending laterally from said member at a distance below the top thereof and provided with an opening, a display member adapted to be disposed at an inclination in reversed positions and having a stud loosely disposed in said opening, said supporting member having supporting engagement with the display member above said means in either of the reversed positions of the display member, said stud and opening permitting the display member to be rotated and bodily rocked in a direction away from the zone of support to effect said reversal, and said means having a part for abutment with said stud to limit lengthwise movement of the display member.

7. In a device of the character described, the combination of an upstanding supporting member, means extending laterally from said member at a distance below the top thereof and provided with an opening, a display member adapted to be disposed at an inclination in reversed positions and having a stud provided with a neck and a head, said neck being loosely disposed in said opening, said supporting member having supporting engagement with the display member above said means in either of the reversed positions of the display member, said stud and opening permitting the display member to be rotated and bodily rocked in a direction away from the zone of support to effect said reversal, and said means having a part for abutment with said head to limit lengthwise movement of the display member.
